UNITED STATES PATENT OFFICE.

RICHARD A. HAEGLIN, OF ST. JOSEPH, MISSOURI.

SAFETY RELEASING DEVICE.

SPECIFICATION forming part of Letters Patent No. 593,844, dated November 16, 1897.

Application filed June 15, 1896. Serial No. 595,608. (No model.)

To all whom it may concern:

Be it known that I, RICHARD A. HAEGLIN, a citizen of the United States, residing at St. Joseph, in the county of Buchanan and State of Missouri, have invented certain new and useful Improvements in Safety Releasing Devices; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in devices for simultaneously releasing all the horses or other animals confined in a stable or the like, in the event of fire or other similar emergency.

20 The invention has for its object the production of a simple and inexpensive means whereby horses or other animals may be independently hitched and unhitched in their respective stalls, and which means can at the same time be operated from one point, so as to simultaneously release all of said animals and cause them to immediately leave said stalls in the event of fire or other similar emergency.

To these ends the invention comprises a 30 supporting-framework, to which are secured a series of brackets or the like, adapted to support a water-pipe which is designed to extend along the line of the stalls of a stable. On this pipe are pivotally mounted a series of 35 cocks having hook-like extensions adapted to engage rings in the halter-straps of the animals confined in said stalls, said hook-like extensions being held in normal engagement with said rings by means of suitable springs 40 secured to the supporting-framework and bearing against extensions of said cocks. Holes or perforations are formed in the water-pipe and are normally covered by the cocks, which latter, however, are provided with slot- 45 ted portions designed to register with said holes or perforations, whereby a stream of water will be ejected. The cocks are all moved back simultaneously by means of a revoluble shaft connected to said cocks by 50 means of cords or chains or may be separately operated by hand.

The invention will be hereinafter fully set

forth, and particularly pointed out in the claims.

In the accompanying drawings, Figure 1 is 55 a view in perspective illustrating my invention. Fig. 2 is a longitudinal sectional view on the line 2 2, Fig. 3. Fig. 3 is a transverse sectional view on line 3 3, Fig. 2. Fig. 4 is a view of a stable-door with the latch of which 60 my invention is connected. Fig. 5 is an enlarged detail sectional view. Fig. 6 is a detail.

Referring to the drawings, A designates a supporting-framework which is designed to extend through the forward ends of a series of 65 stalls and is secured to the end walls thereof in any preferred manner. To this framework are secured a series of brackets a, one for each stall, each of which is provided with two forwardly-extended ears a', provided with coincident holes or openings a², through which is passed a water-pipe a³, which is normally kept filled with water under pressure and from any suitable source. (Not shown.) Between the ears a' of each bracket are secured 70 cocks B, each of which consists of a cylindrical body portion b, fitting around pipe a³ and adapted to turn thereon, and having an upwardly-extended arm b' and a forwardly-extended hook portion b², which is adapted 75 to fit a hole or opening b³, formed in a web b⁴, connecting the forward ends of ears a'. The hook portions b² are normally held in engagement with said holes b³ by means of plate-springs C, secured at one end to arms b', their 80 other ends being secured to framework A. In each cock B, on the under side thereof, is formed a slot b⁵, which is adapted to register with a series of holes or perforations b⁶, formed in pipe a³, whereby water will be ejected when 85 said cock is operated or opened. The webs b⁴ are designed to form seats or rest for rings b⁷, which are provided with concaved portions adapted to fit the body portions b of each cock, and shoulders b⁸, which are designed to fit under overhanging shoulders b⁹ of ears a', the hook portions b² of said cocks being designed to be passed through the holes or openings in said rings. The halter-straps C' are designed to be secured to the rings b⁷ 90 by any suitable means, but preferably by means of spring-hooks C², which prevent the strain incident upon any sudden pulling of the animal at its halter-strap. The cocks B

are each held snugly in place by spring-washers W.

D designates a shaft rotatably mounted in bearings d, secured to framework A and adapted to be rotated by any suitable means, preferably a hand-wheel d', as shown. The shaft D is connected to each cock B by means of cords or chains d², which are secured to eyes d³ on the inner faces of extensions b' of said cocks, the other ends of said cords or chains being connected to similar eyes d⁴, secured to the periphery of said shaft. From this it will be seen that all of the hook portions of said cocks may be raised by the rotation of shaft D. To prevent the return of said hook portions to their normal positions under the action of springs C, I key a ratchet-wheel d⁵ to shaft A, said wheel being normally engaged by a spring-pressed pawl d⁶, pivoted to framework A.

In order to open the stable-door simultaneously with the releasing of the animals confined in the stalls, I connect a rope or cord e to the latch e' of the door E, the other end of said cord being connected to one arm of a bell-crank lever e². From the free end of lever e² I extend a second cord e³, which is wound at its other end around a drum e⁴, keyed on shaft D. By this means the rotation of shaft D will cause the unlatching of the stable-door, and the same will then be readily and quickly opened by means of spring hinges or weights, as shown.

The operations and advantages of my invention are at once apparent from what has been said. It will be observed that each cock is so arranged that its hook may be operated independently of the others, and at the same time the stream of water will not be ejected therefrom unless the said cock is moved back to the utmost limit of its movement. It will also be observed that in the event of fire or like emergency the shaft D can be readily and quickly rotated, so as to release all of the hooks b², which will be disengaged and a stream of water will be thrown into the face of each animal as soon as the slots b⁵ register with the holes or openings b⁶ in the water-pipe, whereby the animals will be frightened into leaving the stalls. Simultaneously with the releasing of the animals the stable-doors will be opened, affording them ready and easy egress. It will be further observed that my improved detaching device comprises but few parts and is not liable to readily get out of order or become deranged.

I claim as my invention—

1. The herein-described device for releasing animals, comprising a supporting-framework, a series of brackets secured thereto, a water-pipe, spring-pressed cocks pivotally mounted on said pipe between said brackets, controlling the flow of water from the pipe, and means for simultaneously moving all of said cocks against the action of their springs, as and for the purpose set forth.

2. The herein-described improved device

for releasing animals, comprising a supporting-framework, a series of brackets secured thereto, a water-pipe, a series of cocks pivotally mounted on said pipe between said brackets controlling the flow of water from the pipe, and having upwardly-extended arms, springs bearing against said arms, and means for simultaneously moving all of said cocks against the action of said springs, as set forth.

3. The herein-described device for releasing animals, comprising a supporting-framework, a series of brackets secured to said framework, a pipe supported by said brackets and designed to be normally filled with water under pressure, a series of cocks pivotally mounted on said pipe and having upwardly-extended arms and lower hook-like extensions, springs bearing against the arms of said cocks, and means for simultaneously moving all of said cocks against the action of said springs, substantially as set forth.

4. The herein-described device for releasing animals, comprising a supporting-framework, a series of brackets secured thereto and each having forwardly-extended arms, a pipe supported by said arms and designed to be normally filled with water under pressure, a web connecting said arms and having a hole or opening therein, a series of cocks pivotally mounted on said pipe and having hook-like portions, springs for normally holding said hook portions in the holes or openings of said webs, and means for simultaneously moving all of said cocks against the action of said springs, substantially as set forth.

5. The herein-described device for releasing animals, comprising a supporting-framework, a series of brackets secured thereto and each having forwardly-extended arms, a web connecting said arms and having a hole or opening therein, a pipe supported by said arms and designed to be normally filled with water under pressure, a series of cocks pivotally mounted on said pipe and having hook-like portions, rings adapted to rest on said webs coincident with the holes or openings thereof, springs adapted to hold said hook portions in engagement with said rings, and means for simultaneously withdrawing all of said hook portions, substantially as set forth.

6. The herein-described device for releasing animals, comprising a supporting-framework, a series of brackets secured thereto and having forward shoulders, webs formed adjacent said shoulders and having holes or openings therein, a pipe supported by said brackets and designed to be normally filled with water under pressure, a series of cocks pivotally mounted on said pipe and having hook-like portions, rings adapted to rest on said webs and having shoulders designed to fit beneath the shoulders of said brackets, springs adapted to hold the hook portions of said cocks in engagement with said rings, and means for simultaneously withdrawing all of said hook portions, substantially as set forth.

7. The herein-described device for releas-

- ing animals, comprising a supporting-framework, a series of brackets secured thereto, a pipe supported by said brackets designed to be normally filled with water under pressure, 5 and having holes or perforations therein, cocks pivotally mounted on said pipe and having hook-like projections and provided with slots adapted to register with said holes or perforations, springs bearing against said 10 cocks and adapted to keep said holes or perforations normally closed, and means for simultaneously moving all of said cocks against the action of said springs, substantially as set forth.
- 15 8. The herein-described device for releasing animals, comprising a supporting-framework, a series of brackets secured thereto, a pipe supported by said bracket designed to be normally filled with water under pressure, 20 and having a series of holes or perforations therein, cocks pivotally mounted on said pipe and having slots adapted to register with said holes or perforations, said cocks being also provided with hook-like projections and upper 25 arms or extensions, springs secured to said framework and bearing against said arms or extensions, and means for simultaneously moving all of said cocks against the action of said springs, substantially as set forth.
- 30 9. The herein-described device for releasing animals, comprising a supporting-framework, a series of brackets secured thereto, a pipe supported by said brackets having holes or perforations therein, cocks pivotally mounted 35 on said pipe and having slots adapted to register with said holes or perforations, said cocks being provided with hook-like projections and upper arms or extensions, springs bearing against said arms or extensions, a 40 rotatable shaft mounted on said framework, and connections between said shaft and the arms or extensions of said cocks, substantially as set forth.
10. The herein-described device for releasing 45 animals, comprising a supporting-framework, a series of brackets secured thereto, a pipe supported by said brackets, cocks pivotally mounted on said pipe and having upper arms or extensions and lower hook-like 50 portions, springs bearing against said arms or extensions, a rotatable shaft mounted on said framework, and connections between said shaft and the arms or extensions of said cocks, substantially as set forth.
- 55 11. The herein-described device for releasing animals, comprising a supporting-framework, a series of brackets secured thereto, a

pipe supported by said brackets and having holes or perforations therein, cocks pivotally mounted on said pipe and having slots adapted to register with said holes or perforations, said cocks being also provided with upper arms or extensions and lower hook-like portions, springs bearing against said arms or extensions, a rotatable shaft mounted on said framework, and connections between said shaft and the arms or extensions of said cocks, substantially as set forth.

12. The herein-described device for releasing animals, comprising a supporting-framework, a series of brackets secured thereto, a pipe supported by said brackets and having holes or perforations therein, cocks pivotally mounted on said pipe and having slots adapted to register with said holes or perforations, 75 said cocks being also provided with upper arms or extensions and lower hook-like portions, springs bearing against said arms or extensions, a rotatable shaft mounted on said framework, chains connected to said shaft and 80 to the arms or extensions of said cocks, means for rotating said shaft, and means for holding said cocks against the action of said springs, substantially as set forth.

13. The herein-described device for releasing animals comprising a supporting-framework, brackets secured thereto, cocks pivotally mounted in said brackets, having upper arms or extensions, springs bearing against said arms or extensions, a rotatable shaft 90 mounted in said framework, connections between said shaft and said cocks, a drum mounted on said shaft, and a cord secured to said drum and designed to be connected to the latch of a stable-door, substantially as set 95 forth.

14. The herein-described device for releasing animals, comprising a framework, brackets secured thereto, a pipe supported by said brackets and having holes or perforations 100 therein, cocks mounted on said pipe and having slots adapted to register with said holes or perforations, said cocks also having lower hook-like extensions, connections between said shaft and said cocks, a drum mounted on 105 said shaft, and a cord secured to said drum and designed to be connected to the latch of a stable-door, substantially as set forth.

In testimony whereof I affix my signature in presence of two witnesses.
